Primary Examiner — Ricky Pham(74) *Attorney, Agent, or Firm* — Kalow & Springut, LLP; David A. Kalow, Esq.(57) **CLAIM**

The ornamental design for a mesh roasting pan, as shown and described.

DESCRIPTION

FIG. 1 is a top view of the mesh roasting pan.

FIG. 2 is a bottom view of the mesh roasting pan.

FIG. 3 is a right side view of the mesh roasting pan.

FIG. 4 is a front side view of the mesh roasting pan.

FIG. 5 is a top perspective view of the mesh roasting pan; and, FIG. 6 is a bottom perspective view of the mesh roasting pan. The broken lines shown in the drawings are for illustrative purposes only and form no part of the claimed design.
